ATTORNEY.

UNITED STATES PATENT OFFICE.

WILLIAM H. ALLEN, OF CAMDEN, NEW JERSEY.

VENTILATING AND DAMPER ATTACHMENT.

SPECIFICATION forming part of Letters Patent No. 231,139, dated August 17, 1880.

Application filed December 15, 1879.

To all whom it may concern:

Be it known that I, WILLIAM H. ALLEN, of the city and county of Camden, and State of New Jersey, have invented a new and useful 5 Improvement in Ventilating and Damper Attachments to Gas-Flues, which improvement is fully set forth in the following specification and accompanying drawings, in which—

Figure 1 is a side elevation of the attachment embodying my invention as applied to a stove. Fig. 2 is a front view thereof.

Similar letters of reference indicate corresponding parts in the two figures.

My invention consists of an improvement in 15 ventilating and damper attachments to heating apparatus, as will be hereinafter set forth.

Referring to the drawings, A represents a vertically-arranged pipe, which is connected to the gas flue or pipe of a stove or heating 20 apparatus, said flue or pipe being shown in dotted lines, as at a, Fig. 1. To the lower end of the pipe A is connected a horizontally-extending pipe, B, which is passed under or along the side of the ash-pit of the stove, and 25 appears at the front thereof, where it is provided with a valve, damper, or register, C.

It will be seen that when it is desired to 30 ventilate the apartment in which the stove is located the register is opened and the air of said apartment is directed to and into the pipe B, and thus discharged into the gas-flue A. The heat of the apartment may thus also be 35 conveyed to or toward the floor thereof for warming the same and displacing the cool and damp air of the apartment, which is carried off through the pipe B.

In the event of raking the fire or removal

of ashes, &c., from the pit or sweeping of the room or existence of odors therein, the open register permits the passage of such created 40 dust or existing odor to enter the pipe B, and the escape of the same to the gas-flue, the conduit of dust from the ash-pit being especially occasioned by the juxtaposition of the mouth of the pipe B to said ash-pit.

Another advantage of the open pipe B is its adaptability as a damper for the fire, as is evident.

When the attachment is not required for service the register is closed.

Owing to the simplicity of the attachment, the pipe B may rest directly on the floor without other means of support.

I am aware that it is not new to connect to the elbow-joint of a stove-pipe a ventilating- 55 pipe which extends vertically and has its lower end open, so as to communicate with the apartment in which the stove is placed.

Having thus described my invention, what I claim as new, and desire to secure by Letters Patent, is—

1. The combination, with a heating apparatus and the vertical pipe A, of the forwardly-projecting horizontal pipe B, substantially as and for the purpose set forth.

2. The vertical pipe A and horizontal pipe B, with a valve or damper, C, combined and operating with a heating apparatus, substantially as and for the purpose set forth.

WILLIAM H. ALLEN.
